UNITED STATES PATENT OFFICE.

CALVIN A. LAUZON, OF GRAND RAPIDS, MICHIGAN, ASSIGNOR, BY MESNE ASSIGNMENTS, TO WM. HEAP & CO., OF MUSKEGON, MICHIGAN, A COPARTNERSHIP.

ELECTRIC OVEN OR COOKER.

1,027,739.

Specification of Letters Patent.

Patented May 28, 1912.

Application filed September 30, 1910. Serial No. 584,745.

To all whom it may concern:

Be it known that I, CALVIN A. LAUZON, a citizen of the United States, residing at Grand Rapids, county of Kent, State of Michigan, have invented certain new and useful Improvements in Electric Ovens or Cookers, of which the following is a specification.

This invention relates to improvements 10 in electric ovens or cookers, and to improvements in such cookers where the heating plates or elements are electrically heated.

The objects of this invention are: First, to provide an improved construction of 15 cover and receptacle for such electric ovens or cookers. Second, to provide improved connections for electrically heating the heating plates of such electric ovens or cookers.

Further objects, and objects relating to 20 structural details, will definitely appear from the detailed description to follow.

I accomplish the objects of my invention by the devices and means described in the following specification.

25 The invention is clearly defined and pointed out in the claims.

A structure which is a preferred embodiment of my invention is clearly illustrated in the accompanying drawing, forming a 30 part of this specification, in which:

Figure 1 is a detail perspective vertical sectional view, through the body of the cooker, the cover being thrown open. Fig. 2 is a detail sectional view through the upper portion of the cooker and the cover or lid therefor in closed position. Fig. 3 is an enlarged detail sectional view, showing the details of the electrical connection for heating the lower plate. Fig. 4 is a detail 40 of the cover and body showing the means of insuring a close contact and fit.

In the drawing, similar reference characters refer to similar parts throughout the several views.

45 Considering the numbered parts of the drawing, the box or main case 1 is supported by corner posts 2 and has cross bars 3, which, with the posts, embrace panels 4 at each side. A bottom 5 extends beneath the same. An inner casing 6, preferably of metal, is separated by suitable insulating or non-conductor material 7 from this outer case. A top 8 connects the inner case 6 to the outer box and is provided with an annular depression 8', which surrounds the

upwardly-projecting rim 6' of the inner shell 6. The rim 6' is formed by seaming the top plate 8 to the inner receptacle or case 6.

The cover 9 is usually hinged and has a 60 slightly projecting cushion 10 near its edge covered over by the plate 9'. The cover therefore contacts with the rim 6 and its outer edge rests with yielding pressure on the plate 8.

65 The top plate 8 is of metal and is watertight, so that steam arising within the cooker will be condensed and accumulated in the depression 8', which prevents the accumulation of moisture within the casing 70 6. As the moisture is retained in this depression 8', it can readily be collected by a sponge or dish-cloth.

Resting within the bottom of the case 6 is the heater plate 11, which is heated by 75 an electric resistance 12, arranged therein. The resistance 12 is connected by pins 14 in the bottom of the receptacle, fitting by a slip fit into sockets 13 in the said plate, whereby the plate can be readily lifted off 80 from the electrical connection when it is desired to heat the plate in an oven, in the event that electric supply is not available. The plate is clamped securely in place by the thumb-screw 15, as clearly appears in 85 Fig. 3. The conductors 16, forming the circuit, are extended through the insulator material 7 to a switch 17 on the outside of the case 1 toward the top—see Fig. 1.

90 The top heating plate 18 is retained in place by loops 19 on the under side of the lid 9. A suitable electric resistance 20 is located in this plate and is provided with suitable perforations for slipping onto the electric connection pins 21, which are on 95 the conductors 22, constituting the electric circuit thereto. These conductors 22 pass to the switch 23 on the top of the lid or cover. It will thus be seen that both the bottom plate 11 and the top plate 18 can 100 be electrically heated, and also that the same are very readily removable so that they can be heated by other means when the electric current is not available.

I desire to state that I prefer to make 105 the outer case of my device of wood and the inner shell 6 of metal, and that the filling 7 is preferably a mixture of cork and asbestos.

110 The structure will be very effective with-

out any electric connection, but, of course, its convenience is greatly enhanced by heating the plates electrically.

The structure can be greatly modified. I
5 wish to claim it broadly, and specifically, as shown.

Having thus described my invention, what I
10 claim as new and desire to secure by Letters Patent is:—

1. In an electric oven or cooker, the combination of the outer casing; an inner metallic shell; suitable insulating material packing between the same; a top plate connecting the said inner shell and outer casing, containing an annular curved depression, surrounding the upper edge of the said inner casing; a cover for the said cooker having a projecting cushion near its edge with a plate covering the same; a heater plate detachably secured within said heater; resistance within the said plate; electric circuits leading to the said plate; and slip pin connections between the electric resistance in the said plate and the said conductor, whereby the plate can be readily removed, all coacting substantially as described and for the purpose specified.

2. In an electric oven or cooker, the combination of the outer casing; an inner metallic shell; suitable insulating material packing between the same; a top plate connecting the said inner shell and outer casing, containing an annular curved depression, surrounding the upper edge of the said inner casing; a cover for the said cooker having a projecting cushion near its edge with a plate covering the same; and a

heater plate detachably secured within said heater, all coacting substantially as described and for the purpose specified.

3. In an electric oven or cooker, the combination of the outer casing; an inner metallic shell; suitable insulating material packing between the same; a top plate connecting the said inner shell and outer casing, containing an annular curved depression, surrounding the upper edge of the said inner casing; and a cover for the said cooker having a projecting cushion near its edge with a plate covering the same, all coacting substantially as described and for the purpose specified.

4. In an electric oven or cooker, the combination of the outer casing; an inner metallic shell; suitable insulating material packing between the same; a cover for the said cooker; a heater plate detachably secured within said heater; resistance within the said plate; electric circuits leading to the said plate; electric connection sockets in said plates; and slip pin connections between the electric resistance in the said plate and the said conductor disposed within the receptacle, whereby the plate can be readily removed, all coacting substantially as described and for the purpose specified.

In witness whereof, I have hereunto set my hand and seal in the presence of two witnesses.

CALVIN A. LAUZON. [L. S.]
